UNITED STATES PATENT OFFICE.

ANDREW KERR, OF BELFAST, IRELAND.

RAILWAY AND LIKE SIGNALING.

1,274,719.

Specification of Letters Patent. Patented Aug. 6, 1918.

Application filed September 6, 1916. Serial No. 118,766.

To all whom it may concern:

Be it known that I, ANDREW KERR, a subject of the King of Great Britain and Ireland, residing at Belfast, Ireland, have invented certain new and useful Improvements in and Relating to Railway and like Signaling, of which the following is a specification.

This invention relates to safety apparatus, used in connection with railway and like signaling, of the class in which a safety device, operated automatically by the passage of a train, sets, at danger, one or more signals in rear of the safety device so that the 10 said signals remain at "danger" and block the line against any following train until the train, which has been instrumental in setting the signals at "danger," has cleared the section guarded by the signals and, when doing 15 this, the train actuates a device which releases the beforementioned signals so that the line may be cleared. In certain signaling apparatus of this class it has heretofore been proposed to use what are known as 20 "slip connection devices" which are inserted in or connected with the usual semaphore signal control gear in such manner that the latter can be disconnected or interrupted to effect "danger" signals and reconnected or 25 restored to allow of "clear" signals being given.

Under my invention the slip connection devices are controlled by levers or so-called "treadles" pivoted or fulcrumed to a track 30 rail in such manner that their free ends can be depressed by the wheel of a passing train and, when depressed, act in such manner as to release the tension of, or exert a pull on, wires or equivalent connected with pawls, or 35 other parts, of the slip connection devices to so move same as to disconnect the semaphore signal gear when a "danger" signal is to be given and to reconnect the signal gear when a clear signal is to be given by the signalman. There may be, in conjunction with 40 each treadle, a resetting cylinder whose piston is connected with the free end of the treadle, the cylinder being secured to or supported by the track rail in order that the 45 relation of the treadle and cylinder to each other and to the track rail will be unaffected by movements of the rail due to the passage of a train, the sinking of the sleepers, or other cause.

50 The signaling arrangement can be adapt-

ed for cross over lines and in this case there is an additional "danger" setting treadle and connections therefrom to a part of the slip connection devices controlling the home and distant signals on both sides of the cross 60 over line whereby said signals would be set at danger when a train crosses from one line to the other and remains within the section guarded by said signals.

In a block signaling arrangement as I 65 prefer to construct the same there is the usual "home" semaphore signal and the "distant" semaphore signal, these signals, as usual, moving automatically to "danger" when the signalman's wire is slackened or 70 disconnected and moved to "clear" on the pull of the signalman's wire. In connection with these semaphore signals are "slip connection" devices operable by a safety treadle on a track rail, this treadle being depressed 75 by the wheel of a passing train and when depressed disconnecting the signalman's wires to both the "home" and "distant" signals so that these will be automatically set at "danger" and the signalman will be un- 80 able to pull them to "clear," the line being consequently "blocked" against a following train. The line remains "blocked" until the train has left the section of the track 85 guarded by the signals whereupon the outgoing train actuates another treadle device adapted to co-act with the slip connection devices so as to reconnect the signalman's wires and permit him to clear the line to an incoming train. Preferably in connection 90 with the "home" and "distant" semaphore signals, there are audible signals operable by treadle levers on the track in the manner set forth in my co-pending application filed the 6th day of September, 1916, Serial No. 95 118765.

In order that my invention may be clearly understood I have hereunto appended explanatory drawings whereon my invention is shown by way of illustration or example, 100 in one form or embodiment thereof.

Figure 1 is a side elevation showing a treadle and a resetting cylinder and Fig. 2 is a cross sectional view on the line $\alpha-\alpha$ Fig. 1.

Figs. 3 and 4 are respectively an end elevation and a side elevation of the slip connection safety device adapted to co-operate with the signal operating gear to insure the giving of a danger signal when required, 110

Fig. 3 being a section on the line $y-y$ Fig. 4.

Fig. 5 is a plan view of Fig. 3.

Fig. 6 is a diagrammatic view showing a 5 block signaling arrangement in accordance with my invention and arranged for distant and home signals on each side of a station.

On the drawings the same reference letters wherever repeated indicate the same or 10 similar parts.

Referring to the drawings and more particularly to Figs. 1 and 2, a treadle 3^a is arranged in conjunction with the "home" signal 2 for the station s and is secured to 15 the track rail r being fulcrumed at t . Near its free end the treadle is connected by pin o^6 to the piston rod of the piston o^1 of a cylinder o which is also secured to and supported by the track rail r . A spring o^4 normally 20 tends to force up the piston and retain the treadle in the operative position. o^2 , o^3 are non-return valves in the piston. o^5 is a restricted air passage. o^7 is an air outlet valve and so is o^8 and both these valves close automatically against any inlet of air. As will 25 be seen the arrangement is such that the relation of the treadle and cylinder to each other and to the track rail will be unaffected by movements of the rail due to sinking of 30 sleepers or any other cause. This treadle is arranged near the station s and when the way is "clear" and the wheel of a passing train depresses this treadle the latter will release the tension on a wire c connected 35 therewith and with a weighted lever c^1 of the slip connection and fulcrumed in a box A , at c^5 , and normally held in the position shown in Fig. 3 by the tension or pull of the wire c when the treadle 3^a is in the up position. 40 When the wire c is thus slackened the weight c^2 on the end of lever c^1 , causes the end c^3 of the "danger" setting swing pawl c^4 , fulcrumed at c^5 to rise, taking with it the projection 45 f^1 on a pawl f which is pivotally secured to a projection f^3 on a counterbar f^1 inserted in a signal wire a^1 thereby disengaging the pawl f from engagement with a slidably supported bar g alongside the bar f^4 and 50 connecting by a wire a with the distant signal 1. When the pawl f is being so lifted a projection f^5 , on the other side of the pawl f , lifts or pushes outward the end i^3 of a swing pawl i , fulcrumed at i^4 , until the pawl 55 bar i^3 passes underneath the projection f^5 on the pawl f and so holds the latter out of engagement with the bar g . When the train depresses the treadle 3^a the piston o^1 in the cylinder o is forced downward and air passes 60 from under the piston o^1 to the top thereof through the non-return valves o^2 and o^3 and, at the same time the spring o^4 is compressed. When the first wheel of the train has passed, the spring o^4 tends to raise the piston and 65 treadle but is retarded by the vacuum

created under the piston o^1 (at the closure of valve o^7) and also by the compression of the air on the top of the piston o^1 through the shutting of the non-return valves o^2 and o^3 so that the treadle is practically held in 70 the down position in order to prevent the wire being jerked by each passing wheel of the train. The hole o^5 , however, allows air to pass slowly from the top to the bottom side of piston o^1 thereby allowing it to return the treadle 3^a to the up position within a predetermined time, regulated by the size of hole o^5 , and ready for the next train. 75 When the pawl f is not lifted out of engagement with the notch in the bar g then the pulling of the signal wire a^1 of the cabin z will, through the medium of the bar f^4 and pawl f , correspondingly move the bar g and as the latter is connected with the wire a connecting with weighted lever 1^b of the 80 distant signal 1 the signalman can pull this semaphore signal to the "clear" position. 85

In the example shown the pulling of the lever 1^b also, through a connection b^1 simultaneously brings a treadle 1^a controlling the 90 audible signal w (similar to that described in my co-pending application) to the "clear" position.

In the case of the "home" signal the audible signal 4 only is preferably simultaneously actuated on the depression of the treadle 3^a , the line signal (or semaphore) 2 being directly connected to the signal cabin z and the counter-bar k , in this case, only controls (in the manner referred to in my 95 co-pending application) the whistle 4, the releasing pawl arrangement being similar to that just described with reference to the "distant" signal. 100

When the train traveling in the direction 105 of the arrow, has passed the station s it makes contact with another treadle 3^b , similar to 3^a , and placed far outside of the station s or at the end of the station section. This treadle 3^b connects, by spring 3^f and wire 3^e , with branch wires 3^d and 3^e leading to levers i^1 and i^2 (see Fig. 6). These levers i^1 and i^2 are used in connection with the swing pawls i (Fig. 3) which the train, by depressing the treadle 3^b , caused to pass 110 under the projection f^5 on the pawl f to hold the latter out of action and now, on the depression of the treadle 3^b , the wire 3^e and branches 3^d and 3^e are put in tension thereby lifting the levers i^1 and i^2 and so 115 causing the swing pawls i to be pulled out of engagement with the projection f^5 of the pawl f and thereby allowing this pawl to drop and engage the counter-bar g so that it connects with the signal-bar f^4 and permits the signalman to give a "clear" signal at both home and distant signals. The 120 spring 3^f takes up or overcomes the inertia of the wire 3^e when being set in motion.

At the "home" signal the treadle 3^a is 125

what I might term the "safety" treadle and when it is depressed the lever c^1 lifts the pawl f out of engagement with the bar g thereby disconnecting the portions a^1 and 5 a of the signal wire from the cabin z to the distant signal 1 so that the signalman cannot give the "clear" signal and the signal 1 and whistle signal w will, under the action of the weighted lever 1^b , automatically 10 go to the "danger" position. Similarly a wire m^1 leading to the lever m is slackened by the depression of the treadle 3^a and the pawl is lifted out of engagement with the counter-bar k and held out of action by a 15 swing pawl i similar to that shown in Fig. 3. In this position the bar k is free to slide and, under the action of the weighted lever 4^b and wire k^1 , brings a treadle 2^a to the "danger" position and ready for whistle 4 20 to be operated by the next passing train. When the train has passed the station s it makes contact with the treadle 3^b and when this treadle 3^b is depressed the wires 3^a and 3^c are placed in tension and lift the swing 25 pawls i and free same from engagement with the pawls f so that the pawls reengage their respective counter-bars and the signalman can then give "clear" signals at both "home" and "distant" signals. The treadle 3^b is fitted with a resetting cylinder o similar to that shown and described with reference to Figs. 1 and 2.

It will be obvious that the apparatus shown for a train approaching the station 35 in the opposite direction will be actuated as herein described with reference to the train traveling in the direction of the arrow v .

At a cross over line y I may place a 40 treadle 2^b and cylinder o and connect same by a wire h with lever h^1 of the distant signal apparatus, by a wire n^1 with a lever n to the home signal apparatus, by a wire q and branch wires q^1 and q^2 with levers m 45 and h^1 of the home and distant signal apparatus of the signals for the opposite direction of travel so that when a train passes over this cross over treadle 2^b then the "distant" and "home" signals in both directions 50 will be set at danger and trains approaching the section in either or both directions will receive warning of danger. The signals on each line will remain at danger until a train has been signaled to proceed and allowed to 55 pass the release treadle 3^b of each line. If desired the distant signals could be connected similarly to the home signals so that the signalman could use both signals to signal a train to proceed, by semaphore, but preferably the driver of the train would still receive the audible warning signal.

In the event of a line being used as a single line my apparatus and its treadles could be lowered and locked out of action.

60 Having now fully described my invention,

what I claim and desire to secure by Letters Patent is:—

1 . In railway signaling, the combination with a signal and means for operating the same, of a device for making and breaking the continuity of said signal operating means, a lever fulcrumed on a track rail and compressible by the wheels of a passing train, and air cushioned means for returning the lever again after each depression, 70 the said lever being connected to the making and breaking device and when depressed operating said device to break the continuity of the signal operating means and when returned permitting the said device to restore 75 the continuity of the signal operating means.

2 . In railway signaling, the combination with a signal and means for operating the same, of a device for making and breaking the continuity of said signal operating 80 means, a lever fulcrumed on a track rail and compressible by the wheels of a passing train, and air cushioned means for returning the lever again after each depression, 85 the said lever being connected to the making and breaking device and when depressed operating said device to break the continuity of the signal operating means and when returned permitting the said device to automatically restore the continuity of the signal 90 operating means.

3 . In railway signaling, the combination with a signal and means for operating the same, of a device for making and breaking the continuity of said signal operating 100 means, a lever fulcrumed on a track rail and compressible by the wheels of a passing train, air cushioned means for returning the lever again after each depression, the said lever being connected to the making and 105 breaking device and when depressed operating said device to break the continuity of the signal operating means and when returned permitting the said device to restore the continuity of the signal operating means, and means for controlling the action of said device.

4 . In railway signaling, the combination with a signal and means for operating the same, of a device for making and breaking 115 the continuity of said signal operating means, a lever fulcrumed on a track rail and compressible by the wheels of a passing train, said lever being connected to the making and breaking device and when depressed operating said device to break the continuity of the signal operating means, and means connected with said lever and comprising an air cylinder, a piston cushioned by the air therein and a spring acting on said 120 piston, for causing said lever to permit the device to act to restore the continuity of the signal operating means.

5 . In railway signaling, the combination with a signal and means for operating the 130

same, of a device for making and breaking the continuity of said signal operating means, a lever fulcrumed on a track rail and depressible by the wheels of a passing train, said lever being connected to the making and breaking device and when depressed operating said device to break the continuity of the signal operating means, and means connected with said lever and comprising an air cylinder carried by the track rail, a piston cushioned by the air in the cylinder and connected to the said lever and a spring acting on said piston, for causing said lever to permit the device to act to restore the continuity of the signal operating means.

6. In railway signaling, the combination with a signal and means for operating the same, of a device for making and breaking the continuity of said signal operating means, a lever fulcrumed on a track rail and depressible by the wheels of a passing train, said lever being connected to the making and breaking device and when depressed operating said device to break the continuity of the signal operating means, automatically acting means for causing the device to restore the continuity of the signal operating means, and air cushioned means carried by the track rail and connected to the said lever for permitting the said automatic means to act.

7. In railway signaling, the combination with a signal and means for operating the

same, of a device for making and breaking the continuity of said signal operating means, a lever fulcrumed on a track rail and depressible by the wheels of a passing train, said lever being connected to the making and breaking device and when depressed operating said device to break the continuity of the signal operating means, means for restoring the continuity of the signal operating means, and air cushioned means for returning said lever after each depression.

8. In railway signaling, the combination with a signal which automatically goes to the "danger" position, of pulling means under the control of the signal man for pulling the signal to "clear", a slip connection device connected with the pulling means, a lever fulcrumed on a track rail and depressible by the wheels of a passing train to operate the slip connection device and cause the disconnection of the pulling means thereby preventing the signal man pulling the signal to the clear position, automatically acting means for again restoring the connection of the pulling means; and air cushioned means acting on the said lever to return it after each depression.

In testimony whereof I affix my signature in presence of two witnesses.

ANDREW KERR.
